FOLDING ROCKING CHAIR

Sidney L. Long, Minneapolis, Minn., assignor to
Ruben W. Anderson, Minneapolis, Minn.

Application January 3, 1938, Serial No. 183,029

5 Claims. (Cl. 155—56)

My present invention relates to chairs of the rocker type and, more particularly, to a folding rocking chair especially well adapted for use on out-of-door porches, lawns, boats and various other places where a comfortable chair is desirable, and which will not be seriously damaged if left out in the weather.

The object of the invention is to provide a folding rocking chair that can be very quickly and easily set up into a plurality of adjustments, in which the back thereof inclines in different positions. Said chair is of rugged construction and cannot collapse after being adjusted into any one of its various different positions. Furthermore, the construction of the chair is such that there is no danger of a person pinching his fingers when sitting in the chair and rocking, or when folding or unfolding the same. The improved chair, when not in use, may be folded into a very compact space and secured against accidental unfolding movement.

To the above end, generally stated, the invention consists of the novel construction and arrangement of parts hereinafter described and defined in the claims.

In the accompanying drawings, which illustrate the invention, like characters indicate like parts throughout the several views.

Referring to the drawings:

Fig. 1 is a left side elevation of the improved chair adjusted to bring its back into its foremost position;

Fig. 2 is a plan view of the improved chair, as shown in Fig. 1;

Fig. 3 is a plan view of the improved chair folded, with some parts broken away and other parts removed;

Fig. 4 is a left side elevation of the chair, as shown in Fig. 3;

Fig. 5 is a detail view with some parts sectioned on the line 5—5 of Fig. 4;

Fig. 6 is a fragmentary detail view showing one of the steps in folding or setting up the chair when adjusted as shown in Fig. 1;

Fig. 7 is a fragmentary detail view principally in section taken on the line 7—7 of Fig. 2, on an enlarged scale;

Fig. 8 is a view in central longitudinal section showing the initial step in setting up the improved chair;

Fig. 9, which corresponds to Fig. 8, shows the chair, by means of broken lines, adjusted to bring its back into an intermediate position and, by means of full lines, adjusted to bring its back into its rearmost position;

Fig. 10 is a view in central longitudinal section showing the chair adjusted into its reclining position, and also showing a foot-rest embodied therein; and

Fig. 11 is a plan view of the foot-rest and fragments of the adjacent portions of the chair.

The numeral 10 indicates a rectangular skeleton base, a seat frame 11, and a back frame 12. Said base comprises a pair of longitudinal side members 13, a front crosstie member 14, and a rear crosstie member 15, all of which are rigidly connected. At the four corners of the base 10 are rubber feet 16 which hold said base just off from the support on which they rest, and these rubber feet also prevent said base from sliding relative to the support.

The rear end of the base 10 is curved as indicated at 17 for a purpose which will hereinafter appear, and in the upper edge portions of the base side members 13, at the rear end portion thereof, are ratchet-like notches 18 having front, rear and intermediate pairs of open seats 18', also for a purpose which will presently appear.

The back frame 12 comprises a pair of rocker arms 19 and top, bottom and intermediate cross-tie members, in the form of slats 20, 21 and 22 rigidly secured to said arms.

Said top slat 20 is on the upper ends of the rocker arms 19, which are cut obliquely and the slats 21 and 22 are on the upper edges of said arms.

The back frame 12 is of such width that its rocker arms 19 transversely embrace the base 10 with a free working fit therebetween. This back frame 12 is upwardly and rearwardly inclined and hingedly secured, at its lower end, to the base 10 by a hinge rod 23, which extends through aligned holes in the base side members 13 and rocker arms 19. Said hinge rod 23 is fixed relative to the base 10 and the rocker arms 19 turn on the ends of said rod which project outwardly of the base 10.

The seat frame 11 comprises a pair of rocker arms 24, a pair of seat-forming slats 25 and 26, and a hinge bar 27. Said slats 25 and 26 rest on the upper edges of the rocker arms 24 with the slat 25 at the extreme outer end portions thereof and with the slat 26 edgewise spaced rearwardly from the slat 25. The hinge bar 27 is on the under-side of the rocker arms 24, at the extreme rear end portions thereof, and which hinge bar and the slat 26 are rigidly secured to said arms. By reference to Fig. 2, it will be noted that the back frame 12 extends between the rocker arms

24 with considerable clearance space therebetween.

The slat 25 is secured to the rocker arms 24 at its rear edge portion by hinges 28 for raising and lowering movements, and which rocker arms are beveled under said slat and normally support the same in a forwardly and downwardly inclined position relative to the slat 26.

Nut-equipped bolts 29, anchored to the slat 25 and working in apertures 30 in the rocker arms 24, limit the lifting movement of said slat to a position in which its under side is in the plane of the upper edges of the rocker arms 24, see Fig. 7. The purpose of hinging the slat 25 will presently appear. The hinge bar 27 is constructed and arranged to be mounted in any one of the pairs of seats 18' to hingedly connect the seat frame 11 to the base 10 and for adjustment toward or from the hinge rod 23 to vary the inclination of the back frame 12.

The two rocker arms 19 and 24 on each side of the chair are connected, above their point of intersection, by a link 31 pivotally attached at its ends to said arms. Blocks 32 on the inner face of the rocker arms 24, and blocks 33 on the outer faces of the rocker arms 19, hold the links 31 spaced from the rocker arms 19 and 24, and which links work in the spaces between said rocker arms with sufficient clearance to prevent a person from getting his fingers pinched between the links 31 and the rocker arms 19 and 24.

The seat and back of the improved chair are formed from a single piece of flexible material which, as shown, is a heavy canvas 34. This canvas 34 is secured at its ends to the outer ends of the two frames 19 and 11 by forming, in the ends of the canvas 34, loops 35 through one of which the slat 20 extends, and through the other of which the slat 25 extends. The canvas 34 is also supported by the slats 21 and 26 over which it loosely extends. The forward movement of the hinge bar 27 on the base 10 and hence the forward endwise movement of the seat frame is limited by a single cable 36 which extends longitudinally of the base 10 at the transverse center thereof.

One end of the cable 36 is anchored to the front face of the cross-tie member 15, and its other end is attached to the hinge bar 27 near the rear edge thereof. When the chair is folded, this cable 36 lies in a notch 37 in the top of the cross-tie member 15 and in a transverse groove 38 in the underside of the hinge bar 27.

The forward swinging movement of the back frame 12 is limited by a pair of forwardly diverging cables 39, the rear ends of which are attached at 40 to the hinge bar 27 near the front edge thereof and in line with the cable 36, and their forward ends are attached to the rocker arms 19, as indicated at 41.

It is important to note that the seats 18' are undercut so that the hinge bar 27 cannot be lifted therefrom except by a forward endwise movement to withdraw said bar therefrom. The length of the cable 36 is such that the hinge bar 27 cannot be released from the foremost pair of seats 18' except by turning the seat frame 11 into substantially a vertical position to put slack in said cable, see Fig. 6.

The chair illustrated in the drawings is capable of three different adjustments by shifting the hinge bar 27 in the different pairs of seats 18', but any number of adjustments may be had by varying the number of pairs of seats

18'. When the chair is adjusted as shown in Fig. 1, the same is in a convenient position, for instance, when a person is sitting at a table. By means of broken lines in Fig. 9, the chair is shown adjusted into its so-called "easy" position, comfortable for a person when conversing or reading, and by full lines in Fig. 9, the chair is adjusted into a reclining position.

10 The mounting of the slat 25 relative to the slat 26 is important as it positions the same so that it will lie flat against the underside of the legs of a person sitting in the chair.

15 The improved chair, when folded, is substantially entirely within the plane of the base 10, see Fig. 4. In this adjustment of the chair, the slat 22 engages the base 10 and positions the rocker arms 19 in the plane of said base. At substantially the final movement of the seat frame 11 into its folded position, the hinged slat 25 engages the base 10 and is raised thereby, as shown by broken lines in Fig. 7, and this permits said seat frame to be positioned in the plane of the base 10, and at which time the slats 25 and 26 rest on the base 10 and the rocker arms 19 rest on the hinge bar 27. The links 31, 20 when the chair is folded, are also in the plane of the base 10.

25 To hold the chair folded, a headed pin 42 is inserted through aligned holes 43 in the side members 13, rocker arms 19 and 24, and link 31, 30 at each side of the chair, see Figs. 3 and 4.

To unfold or set up the chair, it is only necessary to take hold of the back frame 12 at the top thereof, and lift the same. This lifting movement of the back frame 12, acting on the cable 39, moves the seat frame 11 endwise forwardly, and during the initial part of this movement, the hinge bar 27 engages the curved surface 17 on the rear end of the frame 10 and rides over the same and onto said base, where the hinge bar 27 will successively drop into the rear or intermediate ratchet-like notches 18 and be directed thereby into the respective pair of seats 18'. To insert the hinge bar 27 into the front pair of seats 18', the seat frame 12 must be operated as shown in Fig. 6.

35 The positive holding of the hinge bar 27 by the cable 36 in the front pair of seats 18' is highly important for the reason that when the chair is in an upright position, very little forward movement of the seat frame 11, when a person is getting into or out of the chair, would be required to release the hinge bar 27 from said seats 18'.

40 To fold the chair, it is only necessary to disengage the hinge bar 27 from the respective pair of seats 18' and hold the same raised until it is rearward of the rearmost pair of seats 18', while the back frame 12 is being lowered, and during this simple operation, all of the parts 45 of the chair fall into their folded position. When unfolding or setting up the chair, all of the parts thereof assume their operative positions simply by lifting the back frame 12.

45 The invention further includes a foot-rest 44 intermediately pivoted at 45, for turning movement in a vertical plane, to the front end of a rectangular frame 46. This frame 46 includes a pair of longitudinal members 47 and upper 50 and lower crosstie members 48 and 49, respectively, the former of which is on the upper edges of the members 47, and the latter of which is on the under edges thereof. Fixed to the rear ends of the longitudinal members 47 is a pair of hooks 50 arranged to interlock with the hinge

rod 23 and detachably connect the frame 46 to the base 10. The frame 46 is intermediately supported on the crosstie member 14 and is held in an upwardly and forwardly inclined position by the hooks 50 and hinge rod 23. The contour of the frame 46 and the foot-rest 44 is of such proportion as to permit the same to be stored, when not in use, within the base 10. When the frame 46 and foot-rest 44 are thus stored, the hooks 50 rest on a rear member 51 secured to the under-side of the base 10, and the foot-rest 44, forward of the frame 46, rests on the hinge rod 23, and at which time said foot-rest is turned into the plane of the crosstie member 14 with its end portions resting on the longitudinal members 47, which hold said foot-rest against relative turning movement.

In the stored position of the frame 46, the crosstie member 14 is in the same plane as the member 51 and engages the same as a stop to limit the rearward endwise movement of the frame 46 into the base 10, and there is sufficient clearance between the foot-rest 44 and the base member 10 to permit a person to grasp said foot-rest when removing the same from its stored position.

It may be here stated that the chair shown in Figs. 1 to 9, inclusive, will, in actual manufacture, be provided with the crosstie member 51. This crosstie member 51 does not add any additional thickness to the chair when folded, as shown in Figs. 3 and 4, as it lies in the plane of the crosstie member 27.

By pivotally attaching the foot-rest 44 to the frame 46, it is free to move with a person's legs resting thereon, which are in flat contact therewith and thus affords a wide and comfortable support without sharp edges. The open frame 46 makes it possible for a person to step therein to facilitate getting into or out of the chair. When the frame 46 and foot-rest 44 are stored within the base 10, as shown by broken lines in Fig. 10, or attached thereto as shown by full lines, they always retain their set positions when the chair is being moved from place to place.

To remove the frame 46 from the base 10, it is only necessary to swing the same rearwardly to release the hooks 50 from the hinge rod 23 and then lift said frame to withdraw said hooks from the base 10. The holes 43 in the several members of the chair are also extended through the longitudinal frame members 47 to receive the pins 42 when the chair is folded and thereby hold the frame 46 in the base 10.

From the above description, it is evident that the improved chair will not accidentally collapse when a person is getting into or out of the same, nor is it possible for a person to pinch his fingers while rocking or folding or unfolding the chair.

It will be understood that the invention described is capable of various modifications within the scope of the invention herein disclosed and claimed.

What I claim is:

1. A chair of the kind described comprising a base, a seat frame and a back frame, each having at each side of the base a rocker arm, the rocker arms of said two frames being hinged to the base in crossed arrangement, and links 70

connecting the rocker arms of said two frames, said seat frame further including inner and outer cross slats on the upper surfaces of the outer end portions of its rocker arms, said outer slat being hinged at its inner edge portion to the seat frame and normally supported in a forwardly and downwardly inclined position relative to the plane of the inner slat and movable into the plane of the inner slat to permit said two slats to rest on the base when the chair is folded.

2. A chair of the kind described, comprising a base having a hinge seat, an upwardly and rearwardly inclined back frame including a pair of rocker arms pivoted at their lower ends to the base, a seat frame including a pair of rocker arms in crossed arrangement with the first noted rocker arms and having at their lower ends a hinge member releasably held in said seat, a link pivotally connecting the rocker arms on each side of the base and permitting relative endwise and edgewise movements of the two frames, said seat being constructed and arranged to hold the hinge member against removal therefrom, except by forward endwise movement of the seat frame, and a non-stretchable anchor member secured at one end to the base rearwardly of said seat and attached at its other end to the seat frame in offset relation to the seat engaging portion of the hinge member, said anchor member positively holding the hinge member against removal from the seat except when the seat frame is swinging upwardly and rearwardly.

3. The structure defined in claim 2 which further includes a flexible member attached at one end to the seat frame, at its rear end, and attached at its other end to the back frame which flexible member, together with said anchor member, limits the forwardly swinging movement of the back frame, said flexible member also moves the seat frame endwise forwardly during upwardly and forwardly swinging movement of the back frame from its folded position.

4. A chair of the kind described comprising a base having a hinge seat, an upwardly and rearwardly inclined back frame including a pair of rocker arms outwardly of the base and pivoted thereto at their lower ends, a seat frame including a pair of rocker arms outwardly of the first noted rocker arms in crossed arrangement therewith, said seat frame further including a hinge member connecting the respective rocker arms at their lower end portions on the undersides thereof, said hinge member releasably resting in said seat, and a link between the rocker arms on each side of the base and pivotally connecting the same with freedom for relative endwise movements, the rocker arms of the two frames and the links being constructed and arranged to be folded into the plane of the base with the free end portion of the back frame supported on the hinge member of the seat frame.

5. The structure defined in claim 4 in which each frame further includes a cross-tie member arranged to engage the base when the chair is folded and support the rocker arms of each frame in the plane of the base.

SIDNEY L. LONG.
